UNITED STATES PATENT OFFICE.

OTHO N. ROBARDS, OF HENDERSON, KENTUCKY.

SEAT-RAIL ATTACHMENT FOR TOP-CARRIAGES.

1,302,223.

Specification of Letters Patent. Patented Apr. 29, 1919.

Application filed July 11, 1916, Serial No. 108,652. Renewed March 14, 1919. Serial No. 282,735.

To all whom it may concern:

Be it known that I, Otho N. Robards, a citizen of the United States, and a resident of Henderson, in the county of Henderson 5 and State of Kentucky, have made an Improved Seat-Rail Attachment for Top-Carriages, of which the following is a specification.

The invention is embodied in the form and 10 construction of the seat-rail proper, the means of attachment of the same to the carriage seat-irons, and the provision of a hook adapted to engage the front brace of a carriage top for holding the latter distended.

15 The following is a description of the invention, reference being had to the accompanying drawing, in which:—

Figure 1 is a side view showing my improvement applied to a carriage-seat and 20 top.

Fig. 2 is an enlarged vertical section on the line 2—2 of Fig. 1.

Fig. 3 is an enlarged detailed section showing engagement of the seat-rail, lug or hook 25 with a seat iron.

Fig. 4 is an enlarged cross section of the front carriage-top brace.

Fig. 5 is a perspective view of the complete seat-rail attachment.

30 In Figs. 1 and 5, the numeral 1 indicates the detachable seat-rail, and numerals 1^a and 1^b indicate its upwardly extended ends, which are curved inwardly or toward each other. The underside of the seat-rail is provided 35 with a hook or lug 2, projecting rearwardly, and 3 indicates a screw-stud adapted to receive a nut, as shown in Fig. 1.

To attach the rail 1 to the seat-irons 4 and 5, the hooked lug 2 is inserted in a hole 40 formed in the rear seat-iron 4, as shown in Fig. 3, while the stud 3 is inserted in the front seat-iron 5, as shown in Fig. 2, and a nut is screwed thereon, thus securing the

rail tightly in place by the aid of a single fastening.

45 As shown in Fig. 1, a normally vertical bow 6 is pivoted to the extremity 7 of the forward end of seat-rail 1 and front and rear inclined bows 12 and 13 are pivoted to the lower portion of the said bow 6. A rear vertical bow 8 is pivoted to the rear end of the seat-rail. The front ends of the several bows 6, 8, 12, and 13 are pivoted to the horizontal jointed braces 9, 9^a, 9^b. Thus all of the said bows and braces are adapted to be folded 50 55 backward.

For holding the carriage-top frame extended, as indicated in Fig. 1, I employ a hook 10, which is pivoted to the front hook 1^b of the rail-seat, and its free end is adapted 60 to engage a knob or stud 11, which is adjustably secured to the front brace or bow 12 by means of a screw-clamp.

It will be observed that the hook 10 is adapted to swing vertically in a plane parallel 65 to the seat-rail 1, and that its free end may be easily attached to, or detached from, the knob or stud 11. When so engaged, as shown, it serves to hold the carriage-top rigidly distended and upright, and it may be 70 as easily detached when it is required to lower the top.

I claim:—

The combination with a carriage top having horizontally arranged jointed braces and 75 a seat-rail whose front end is curved upwardly and rearwardly, of vertical bows 6 and 8 and inclined front and rear bows 12 and 13, the latter two being pivoted to the lower portion of the intermediate bow 6 and 80 a hook pivoted to the front end of the seat-rail and adapted to engage the front bow 12 for holding the carriage top distended, as 85 shown and described.

OTHO N. ROBARDS.
